Letters Patent No^o 910. Dated July 14, 1857.

The schedule referred to in these Letters Patent, and making part of the same.

To all whom these Presents shall come.

Be it known that we, James Maguire, Joseph A. Read & Duncan Wright, of Philadelphia, and State of Pennsylvania, have invented a new design for a cooking stove, and that the following is a full, clear and exact description of the principle or character which distinguishes it from all other things before known, and of the usual manner of making, modifying and using the same, reference being had to the accompanying drawings.

Fig: 1. Represents the side of the stove with oven door illustrating the design thereof.

Fig: 2. Represents the front plate of the stove illustrating the design thereof.

These drawings illustrate our design for the Star Cooking Stove, other parts of the stove being plain and ornamental at pleasure.

What we claim as our invention is the design for star Cooking Stove, as hereinabove illustrated and set forth.
